[57] ABSTRACT

Certain novel 4-amino-3,5-dinitrobenzenesulfonyl azides are described, with their preparation and use as herbicides.

6 Claims, No Drawings

AROMATIC SULFONYL AZIDES

BACKGROUND OF THE INVENTION

1. Field of the Invention

This invention relates to a novel class of benzenesulfonyl azides ring substituted with a secondary amino and two nitro groups which exhibit high herbicidal activity.

2. Description of the Prior Art

No art is known which anticipates the herbicidal amino-dinitrobenzenesulfonyl azides of this invention. U.S. Pat. No. 3,376,127 discloses the use of alkali metal azides, alkali earth metal azides, hydrazoic acid, ammonium and quaternary ammonium azide, double azide salts and carbonyl azides as aquatic herbicides. Other related art includes U.S. Pat. No. 3,367,949 which discloses a series of substituted 3,5-dinitrosulfanilamides as herbicides.

SUMMARY OF THE INVENTION

A new series of benzenesulfonyl azides substituted para to the azidosulfonyl moiety with a secondary amino moiety and in the meta position with nitro groups has been discovered. These novel compounds have shown high activity in the control of several species of grasses and broad leaf weeds which menace food and forage crops.

The invention accordingly is the new class of aromatic azides hereinbefore described, their use as herbicides and herbicidal formulations containing them.

DESCRIPTION OF THE PREFERRED EMBODIMENTS

The novel compounds of this invention can be represented by the general formula I:

wherein R¹ and R² each represents alkyl of up to four carbon atoms, alkenyl of up to four carbon atoms or cycloalkyl of up to six carbon atoms. Any of these alkyl groups can be of either branched-chain or straight chain configuration.

Exemplary species of the class of the invention include:

- 4-(dimethylamino)-3,5-dinitrobenzenesulfonyl azide
- 4-(dibutylamino)-3,5-dinitrobenzenesulfonyl azide
- 4-(diisopropylamino)-3,5-dinitrobenzenesulfonyl azide
- 4-(butylmethylamino)-3,5-dinitrobenzenesulfonyl azide
- 4-(ethylpropylamino)-3,5-dinitrobenzenesulfonyl azide
- 4-(dicyclopropylamino)-3,5-dinitrobenzenesulfonyl azide
- 4-(dicyclopentylamino)-3,5-dinitrobenzenesulfonyl azide
- 4-(dicyclohexylamino)-3,5-dinitrobenzenesulfonyl azide
- 4-(cyclopentylcyclohexylamino)-3,5-dinitrobenzenesulfonyl azide
- 4-(ethylcyclopropylamino)-3,5-dinitrobenzenesulfonyl azide

- 4-(diallylamine)-3,5-dinitrobenzenesulfonyl azide
- 4-(dicrotylamino)-3,5-dinitrobenzenesulfonyl azide
- 4-(allylpropylamino)-3,5-dinitrobenzenesulfonyl azide

Preferred because of their especially effective herbicidal properties are the sulfonyl azide compounds in the subclass wherein R¹ is alkyl of up to four carbon atoms or cycloalkyl of up to four carbon atoms and R² is alkyl of up to four carbon atoms or alkenyl of up to three carbon atoms.

Examples of such preferred herbicides are:

- 4-(dipropylamino)-3,5-dinitrobenzenesulfonyl azide
- 4-(diethylamino)-3,5-dinitrobenzenesulfonyl azide
- 4-(ethylpropylamino)-3,5-dinitrobenzenesulfonyl azide
- 4-(butylethylamino)-3,5-dinitrobenzenesulfonyl azide
- 4-(allylcyclopropylamino)-3,5-dinitrobenzenesulfonyl azide
- 4-(butylpropylamino)-3,5-dinitrobenzenesulfonyl azide
- 4-(allylcyclobutylamino)-3,5-dinitrobenzenesulfonyl azide
- 4-(dimethylamino)-3,5-dinitrobenzenesulfonyl azide
- 4-(methylpropyl)-3,5-dinitrobenzenesulfonyl azide

The compounds of the invention are solid at ambient temperature. They may be suitably formulated for use as herbicides, as wettable powers, dusts, granules, solutions, emulsifiable concentrates, emulsions and pastes.

Wettable powers are usually compounded to contain 25, 50, 75 or up to 85 percent of toxicant and usually contain, in addition to solid carrier, 3-10 percent of a dispersing agent and, where necessary, 0-10 percent of stabilizer(s) and/or other additives such as penetrants or stickers. Dusts are usually formulated as a dust concentrate having a similar composition to that of a wettable power but without a dispersant, and are diluted in the field with further solid carrier to give a composition usually containing ½-10 percent of toxicant.

Granules are usually prepared to have a size between 10 and 100 BS mesh, and may be manufactured by agglomeration or impregnation techniques. Generally, granules will contain ½-25 percent of toxicant plus additives such as stabilizers, slow-release modifiers, binding agents, etc. Emulsifiable concentrates usually contain, in addition to the solvent, and, when necessary co-solvent, 10-50 percent s/v toxicant, 2-20 percent w/v emulsifiers and 0-20 percent of appropriate additives such as stabilizers, penetrants and corrosion inhibitors. Pastes are compounded so as to obtain a stable flowable product and usually contain 10-60 percent toxicant, 2-20 percent of appropriate additives and, as carrier, water or an organic liquid in which the toxicant is substantially insoluble. Except where indicated otherwise, all percentages given in this paragraph are percentages by weight.

The herbicidal compounds of this invention may be prepared by the reaction of a benzenesulfonyl chloride of the formula II:

wherein R¹ and R² are as defined above with an alkali metal or ammonium azide, e.g., sodium azide. The reaction is suitably carried out in a mixed water/polar organic solvent medium, the azide being introduced to the reaction in aqueous solution and the sulfonyl chloride being introduced in a solvent which is miscible with water, e.g., lower alkanols or dioxane. The reaction will proceed satisfactorily at temperatures ranging from about 25° to 100° C. Dependent on the reaction temperature utilized, the reaction is ordinarily complete in 1 to 5 hours.

The substituted benzenesulfonyl chlorides described by formula II are known compounds and can be prepared from p-chlorobenzene-sulfonic acid using a four-step synthesis scheme. In the initial reaction step the p-chlorobenzenesulfonic acid is nitrated in the 3 and 5 position on the ring with a mixture of 90 percent nitric acid in 65 percent oleum. The dinitro intermediate is then converted to an alkali metal salt, e.g., sodium or potassium, by neutralizing with the corresponding hydroxide and the salt compound is reacted with a secondary amine of the formula R¹F²NH wherein R¹ and R² are as defined above to yield the alkali metal salt of a 4-(N,N-disubstituted amino)-3,5-dinitrobenzenesulfonic acid. This alkali metal salt is then converted to the corresponding sulfonyl chloride by treatment with phosphorus pentachloride in a solution of phosphoryl chloride.

The compounds of the invention, processes for their preparation and their herbicidal activity, are illustrated by the following examples, in which parts by weight (w) and parts by volume (v) bear the same relation as the kilogram to the liter and all temperatures are in degrees centigrade.

EXAMPLE I

4-(Dipropylamino)-3,5-dinitrobenzenesulfonyl azide

To a solution of 3,5-dinitro-4-(dipropylamino)benzenesulfonyl chloride (9.15 w) in ethanol (200 v) was added at room temperature a solution of sodium azide (6.5 w) in water (25 v) in one portion. After 1 hour, water (300 v) was added and the yellow crystalline solid which precipitated was filtered and dried to give 4-dipropylamino-3,5-dinitrobenzenesulfonyl azide (5.5 w) melting at 70°-75°. The structure was confirmed by infrared spectral and elemental analyses.

Analysis (Percent by Weight)

Calculated: C - 38.7 H - 4.7 N - 22.6
Found: C - 28.5 H - 4.7 N - 22.7

EXAMPLE II

4-(Butylethylamino)-3,5-dinitrobenzenesulfonyl azide

4-(Butylethylamino)-3,5-dinitrobenzenesulfonyl chloride (18.3 w) in dioxane (50 v) was added dropwise with stirring to a solution of sodium azide (3.9 w) in water (50 v). The mixture was heated to 70° for 3 hours, poured over ice water and extracted with 3 × 75 v portions of methylene chloride. The combined methylene extracts were dried over anhydrous magnesium sulfate, filtered and concentrated to 18 g of red oil. This oil was crystallized from ether to yield a yellow crystalline solid, 4-(butylethylamino)-3,5-dinitrobenzenesulfonyl azide (16 w) melting at 75°-78°. The structure was confirmed by infrared spectrum, nuclear magnetic resonance and elemental analyses.

Analysis (Percent by Weight)

Calculated: C - 38.7; H - 4.7; N - 22.6
Found: C - 39.0; H - 4.6; N - 23.0

EXAMPLE III

4-(Diethylamino)-3,5-dinitrobenzenesulfonyl azide

A solution of 4-(diethylamino)-3,5-dinitrobenzenesulfonyl chloride (18.4 w) in dioxane (100 v) was added rapidly with stirring to a solution of sodium azide (4 w) in water (100 v). This mixture was heated to 80° for 3 hours, poured over ice water and filtered. Recrystallization from ether afforded an orange crystalline solid, 4-(diethylamino)-3,5-dinitrobenzenesulfonyl azide (17 w), melting at 99°-101°. The structure was confirmed by infrared spectrum, nuclear magnetic resonance and elemental analyses.

Analysis (Percent by Weight)

Calculated: C - 34.9; H - 3.5; N - 24.4
Found: C - 34.8; H - 3.6; N - 25.0

EXAMPLE IV

4-(Allylcyclopropylamino)-3,5-dinitrobenzenesulfonyl azide

To a solution of sodium azide (0.6 w) in water (20 v) was added at room temperature a solution of 3,5-dinitro-4-(allylcyclopropylamino)-benzenesulfonyl chloride (1.0 w) in acetone (20 v). The mixture was heated for one hour on a steam bath. Acetone was removed under vacuum. The residual solid was mixed with water (200 v) and filtered. The filter cake was recrystallized from ether to yield the product as a yellow crystalline solid (1.0 w), melting at 78°-80°. The

structure was confirmed by infrared spectrum, nuclear magnetic resonance and elemental analyses.

Analyses (Percent by Weight)

Calculated: C - 39.2; H - 3.3; N - 22.8
Found: C - 38.7; H - 3.3; N - 23.2

EXAMPLE V

Pre-emergence herbicidal activity of the typical compounds of the invention was evaluated by planting weed seeds in soil held in large test tubes, the soil having been treated with the test compound at the rate of 1 and 10 milligrams of test compound per tube, respectively. Seeds of watergrass (*Echinochloa crusgalli*) and cress (*Lepidium sativum*) were germinated in treated soil under controlled conditions of temperature and light for 12 to 13 days prior to evaluation of the effectiveness of the treatments. At that time, the germination was noted and the treatments were rated on a 0 (no effect) to 9 (all dead) scale. The results are summarized in Table I.

Post emergence herbicidal activity was evaluated by spraying dilute suspensions of the test compound in a 1:1 mixture of acetone and water with 0.5 percent wetting agent on crabgrass (*Digitaria sanguinalis*) and pigweed plants (*Amaranthus* sp) grown under controlled conditions at the rates of 1 and 10 pounds test compound per acre. After the plants were held for 10 to 11 days, they were rated for treatment on a 0 (no effect) to 9 (total plant kill) scale. The results of these tests are shown in Table I.

We claim as our invention:

1. A compound of the formula:

25 wherein R¹ and R² each represents alkyl of up to four carbon atoms, alkenyl of up to four carbon atoms or cycloalkyl of up to six carbon atoms.

2. A compound according to claim 1 wherein R¹ is alkyl of up to four carbon atoms or cycloalkyl of up to four carbon atoms and R² is alkyl of up to four carbon atoms or alkenyl of up to three carbon atoms.

3. The compound according to claim 2 wherein R¹ and R² each is propyl.

35 4. The compound according to claim 2 wherein R¹ is butyl and R² is ethyl.

5. The compound according to claim 2 wherein R¹ and R² each is ethyl.

6. The compound according to claim 2 wherein R¹ is cyclopropyl and R² is allyl.
